US00D882913S

(12) **United States Design Patent** (10) **Patent No.:** **US D882,913 S**
(45) **Date of Patent:** **** May 5, 2020**

(54) **FOOTWEAR SOLE**

(71) Applicant: **Saucony, Inc.**, Waltham, MA (US)

(72) Inventor: **Christopher J. Mahoney**, Concord, MA (US)

(73) Assignee: **Wolverine Outdoors, Inc.**, Rockford, MI (US)

(**) Term: **15 Years**

(21) Appl. No.: **29/660,747**

(22) Filed: **Aug. 22, 2018**

Related U.S. Application Data

(63) Continuation of application No. 29/604,418, filed on May 17, 2017, now Pat. No. Des. 831,315.

(57) **CLAIM**

The ornamental design for footwear sole, as shown and described.

DESCRIPTION

FIG. 1 is a perspective view of the footwear sole embodying the new design;

FIG. 2 is a right side view thereof;

FIG. 3 is a left side view thereof;

FIG. 4 is a front view thereof;

FIG. 5 is a rear view thereof; and,

FIG. 6 is a close up view thereof, taken from view VI in FIG. 1.

FIGS. 1-6 show features of an article of footwear in broken lines. These features are shown for environmental purposes and do not form any part of the claimed design. Further, the broken lines immediately adjacent the solid-line portions of

(Continued)

the design form the boundary of the design, with the broken lines forming no part of the claimed design.

1 Claim, 5 Drawing Sheets
